SELF-OPENING DIE HEAD

Albert F. Breitenstein, New Haven, Conn., assignor to The Geometric Tool Company, New Haven, Conn., a corporation of Connecticut

Application June 3, 1939, Serial No. 277,148

16 Claims.

The present invention relates to improvements in self-opening die heads. More particularly, the present invention relates to improvements in self-opening die heads of the type employing an oscillating chaser-operating member.

One of the objects of the present invention is to provide a superior self-opening die head of the character above referred to, and which is reliable in its operation and economical to produce and maintain.

Another object of the present invention is to provide a superior self-opening die head of the type above referred to, and characterized by such a degree of compactness as will enable the die head to be used in confined and limited spaces.

A further object of the present invention is to provide a superior die head of the type referred to and which may be relied upon to accurately and uniformly retire its chasers from the work at a predetermined point thereon during repeated cycles of operation of the die head.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

30 Fig. 1 is a view in side elevation of a self-opening die head embodying the present invention;

Fig. 2 is a front-face view thereof;

Fig. 3 is a rear-face view thereof;

35 Fig. 4 is a longitudinal sectional view thereof taken on the line 4—4 of Fig. 2 and illustrating the parts in the positions which they assume when the chasers are in their advanced or thread-cutting positions;

40 Fig. 5 is a view corresponding to Fig. 4, but illustrating the parts in the positions due to them at the instant that the latch-member reaches a position to permit the chasers to be retired out of engagement with the work;

45 Fig. 6 is a fragmentary sectional view taken on the line 6—6 of Fig. 1;

Fig. 7 is a transverse sectional view taken on the line 7—7 of Fig. 4;

Fig. 8 is a similar view taken on the line 8—8 of Fig. 4;

50 Fig. 9 is a view in central-longitudinal section taken on the line 9—9 of Fig. 2, but showing the position which the parts assume at the instant that the latch-member reaches its releasing position as a result of the forward movement of the chaser-carrying member and associated parts

(Cl. 10—96)

with respect to the mounting-member which movement has been effected by forward draft exerted upon the chasers by the work being threaded;

Fig. 10 is a perspective view of the mounting-member;

Fig. 11 is a perspective view of the L-shaped latch-member;

Fig. 12 is a transverse sectional view taken on the line 12—12 of Fig. 7;

Fig. 13 is a transverse sectional view taken on the line 13—13 of Fig. 8;

Fig. 14 is a broken view in transverse section taken on the line 14—14 of Fig. 7; and

Fig. 15 is a similar view taken on the line 15—15 of Fig. 7.

The particular self-opening die head herein chosen for the illustration of the present invention, includes a mounting-member generally designated by the reference character 20 and including a rearwardly-extending tubular shank 21 which is adapted to be mounted in the turret or other appropriate feature of a screw-machine or the like. The said shank 21 is preferably formed integral with, and projects rearwardly from, a 20 plate-like body-portion 22 from the front portion of which latter forwardly extends a tubular guide-portion 23. The said guide-portion 23 extends with a close sliding fit into an axial bearing-passage 24 formed in a chaser-carrying member generally designated by the reference character 25.

The chaser-carrying member 25 is formed in its forward face with four (more or less) corresponding radial grooves 26 which intersect both the inner and outer peripheries of the adjacent portions of the chaser-carrying member. Installed in each of the grooves 26 respectively, is a radially-movable chaser 27 provided in its rear face with a rearwardly-opening and transversely-extending notch 28. The respective notches 28 in the rear faces respectively of the chaser 27 are slightly inclined, as shown, and each thereof receives the adjacent one of four similarly inclined cam-lugs 29 forwardly-projecting from an oscillating chaser-operating ring 30.

The said oscillating chaser-operating ring 30 is mounted with capacity for oscillating movement upon the central-portion of the chaser-carrying member 25 and is retained in place thereon against relative rearward displacement by a retaining-plate 31. The said retaining-plate 31 is secured to the said chaser-carrying member 25 by means of two (more or less) screws 32—32 as is shown in Figs. 3 and 12. The said retaining-plate 31 is centrally apertured to receive an 50 55

nular locating-flange 33 projecting rearwardly from the chaser-carrying member 25 and having its interior surface forming part of the bearing passage 24 receiving the guide-portion 23 of the 5 mounting-member 20.

For the purpose of coupling the retaining-plate 31 and hence the chaser-carrying member 25 and associated parts, to the mounting-member 20, the body-portion 22 of the said mounting-member is 10 provided with two (more or less) coupling-pins 34—34 as is shown particularly well in Figs. 8 and 13. The said coupling pins 34—34 project forwardly from the body-portion 22 of the mounting-member 20 and extend with a close sliding fit 15 respectively, into the adjacent one of two corresponding coupling-passages 35—35 extending from front to rear through the retaining-plate 31 adjacent the outer periphery thereof.

From the foregoing it will be seen that the interfitting of the coupling-pins 34—34 and the coupling-passages 35—35 will serve to couple the mounting-member 20 to the retaining plate 31 and hence also to the chaser-carrying member 25 and the parts carried thereby. Relative axial 25 movement is, however, provided for between the coupling-pins 34—34 and the coupling-passages 35—35 for the purpose as will more fully herein-after appear.

To normally but yieldingly hold the chaser-carrying member 25 and the parts carried thereby in their rearmost positions with respect to the mounting-member 20, two (more or less) retracting-springs 36—36 are respectively located in spring-pockets 37—37 formed partly in the 30 chaser-carrying member 25 and partly in the retaining-plate 31 carried by the said chaser-carrying member, as is shown particularly well in Fig. 14. The said retracting-springs 36—36 respectively encircle screw-studs 38—38 which are 35 threaded into and project forwardly from the body-portion 22 of the mounting-member 20. Each of the retracting-springs 36—36, thrusts at its forward end, against the under face of the head of its complementary screw-stud 38 and 40 thrusts, at its rear end, against the rear end-wall of the particular spring-pocket 37 in which the retracting-spring in question is located.

For the purpose of normally maintaining the rear face of the retaining-plate 31, which forms a unitary part of the chaser-carrying member 25, in spaced relationship with respect to the forward face of the body-portion 22 of the mounting-member 20, and to provide a cushioning action for the purpose as will more fully herein-after appear, two helical cushioning-springs 39—39 are employed (Figs. 7 and 15). The said cushioning-springs 39—39 are respectively housed within spring-pockets 40—40 formed partly within the chaser-carrying member 25 and partly within 50 the retaining-plate 31. The said cushioning-springs 39—39 each press against the front end-wall of its complementary spring-pocket 40 as is shown in Fig. 15. The rear end of each of the cushioning-springs 39—39 respectively, thrusts 55 rearwardly against a cushioning-plunger 41, one of which latter is mounted with capacity for reciprocatory movement in each of the spring-pockets 40—40.

Each cushioning-plunger 41—41 above referred 70 to, thrusts at its rear end against the forward face of the body-portion 22 of the mounting-member 20 and is formed with an annular stop-flange 42 which is normally engaged with the rear wall of the complementary spring-pocket 40

to limit the rearward movement of the cushioning-plunger 41 of which it forms a part.

The retracting-springs 36—36 and the cushioning-springs 39—39 are preferably so proportioned in the elastic power which they provide, 5 that the said cushioning-springs 39—39 dominate the retracting-springs 36—36, whereby in the absence of extraneous forces the retracting-plungers 41—41 will always hold the rear face of the retaining-plate 31 in spaced relationship forwardly 10 of the front face of the body-portion 22 of the mounting-member 20, despite the continued effort of the retracting-springs 36—36 to bring the two said faces together.

To provide for eliminating the cushioning-action provided for by the cushioning-springs 39 and associated parts, the body-portion 22 of the mounting-member 20 is provided near its periphery with a stop-screw 43 extending in parallelism with the axis of the die head and adapted to be 20 threaded forwardly to engage with the rear face of the retaining-plate 31 as is shown in Fig. 1 of the drawings. Extending perpendicularly with respect to the stop-screw 43 is a binding-screw 44 also mounted in the body-portion 22 of the 25 mounting-member 20 and serving, when screwed home, to lock the stop-screw 43 in any given position of adjustment.

In its rear portion, the chaser-operating ring 30 is formed with a rearwardly-opening annular-groove 45 in which is mounted a helical chaser-retracting spring 46 as is especially well shown in Fig. 7. The said chaser-retracting spring thrusts at one end against a stud 47 which is rigidly mounted in the retaining-plate 31 and which 35 projects forwardly therefrom into the annular-groove 45 in the rear face of the chaser-operating ring 30, as will be seen by reference to Figs. 7 and 12 in particular. The opposite end of the chaser-retracting spring 46 thrusts against a stud 48 40 rigidly mounted in the chaser-operating ring 30 and projecting into the groove 45 therein, as will be seen by reference to Figs. 7 and 14 in particular.

As thus arranged, the chaser-retracting spring 46 exerts a constant but yielding effort to turn 45 the chaser-operating ring 30 in the direction of the arrows 49 shown in Figs. 2 and 7, to thus cause the segmental inclined cam-lugs 29 to move the chasers 27 outwardly into their re-tired positions.

Rigidly installed in the rearwardly-opening annular-groove 45 of the chaser-operating ring 30, is a segmental latch-block 50 which is held in place by a pin 51 as is indicated in Fig. 7. One end of the latch-block 50 provides a latching 55 abutment 52 which is adapted to be engaged by one side of a latching-pin or -abutment 53 rigidly secured to and forwardly projecting from the inner end of a plate-like arm 54 forming a part of an L-shaped latch-member generally designated by the reference character 55. The said latch-member 55 also includes a forwardly-projecting tubular arm 56 extending in substantial parallelism with the axis of the die head and provided in its forward portion with a threaded bore 60 57 from the rear end of which extends a relatively small-dia-metered guide-passage 58. Threaded into the bore 57 in the tubular arm 56 of the latch-member 55 is a tripping-screw 59 having a nut-like head 60 formed integral therewith 65 and located forwardly of the front end of the arm 56.

The tripping-screw 59 is axially adjustable with respect to the latch-member 55 and for the purpose of firmly locking the said tripping-screw in 70 75

any given position within its range of adjustment, the said tripping-screw has threaded onto it to the rear of the head 60, a lock-nut 61 which is adapted to be jammed against the forward face 5 of the arm 66 of the latch-member 55, as is shown in the drawings. The tripping-screw 59 is formed with a relatively-slender stem 62 which extends rearwardly through the guide-passage 58 in the latch-member 55, and also through a passage 63 10 formed in a radial-arm 64 formed integral with and offsetting from the body-portion 22 of the mounting-member 20. Axially in line with the passage 63, the arm 64 is formed in its rear face with a rearwardly-opening cylindrical recess 65 15 which normally receives a coupling-nut 66 having diametrical grooves 67 in its rear face to receive a locking-pin 68 extending through the threaded rear-portion of the stem 62 upon which the coupling-nut 66 is mounted. The coupling-nut 66 is also formed with a forwardly-projecting annular-sleeve 69 which may move freely 20 through the passage 63 in the arm 64 before referred to.

25 Encircling the forward portion of the tubular arm 56 of the L-shaped latch-member 55, is a tubular-spring-plunger 70 having a radially-extending annular flange 70a and normally thrusting at its forward edge against the rear face of the lock-nut 61. The said tubular spring-plunger 70 is adapted to reciprocate in a spring-pocket 30 71 having its axis extending parallel with the axis of the die head and formed in a forwardly-extending tubular portion 72 of an L-shaped arm generally designated by the reference character 35 73 and formed integral with the retaining-plate 31 before referred to. Leading rearwardly from the spring-pocket 71 in the tubular portion 72 is a bearing-passage 74 extending through the rear face of the arm 73 and intersecting a radially-extending recess 75 formed in both the rear face 40 of the said arm 73 as well as in the rear face of the retaining-plate 31 proper. Leading forwardly from the inner end of the recess 75 just referred to in parallelism with the bearing-passage 45 74, is a clearance passage 76 accommodating the latching-pin 53 and permitting the same to be extended forwardly into the rearwardly-facing annular groove 45 in the chaser-operating ring 30, as is clearly shown in the accompanying drawings.

Located in the rear portion of the spring-pocket 71 in the tubular portion 72 of the arm 73 is a helical latching-spring 77. The said latching-spring 77 encircles the tubular arm 56 of the latch-member 55 and thrusts at its forward end against the rear face of the tubular spring-plunger 70 and at its rear end the said spring thrusts against the rear wall of the spring-pocket 71. In this manner the latching-spring 77 exerts a constant but yielding effort to shift the entire latch-member 55 forwardly in a direction required to interpose the latch-pin 53 thereof into the path of movement of the latching-abutment 52 carried by the chaser-operating ring 30, as before described.

For the purpose of limiting the oscillating movement of the chaser-operating ring and to provide for releasing such restraint to a necessary degree, a radially retractile limiting-plunger 78 is employed as is particularly well shown in Fig. 6. The said limiting-plunger 78 is provided with a relatively-slender stem 79 and is mounted for reciprocatory movement in a housing 80 partly threaded into the chaser-operating ring 30 and partly projecting from the outer periphery of the

latter. The limiting-plunger 78 is yieldingly urged inwardly by a helical spring 81 which encircles its stem 79 and which is enclosed within the housing 80. The outer end of the stem 79 of the limiting-plunger 78 is provided with a 5 peripherally-knurled finger-piece 82 by means of which the limiting-plunger may be drawn radially outwardly against the tension of the spring 81. The inner end of the limiting-plunger 78 enters an arcuate limiting-recess 83 formed in 10 the outer surface of the chaser-carrying member 25. When the chaser-operating ring 30 is released to the action of the chaser-retracting spring 46 in a manner as will hereinafter appear, the limiting-plunger 78 will be brought into engagement with the end-wall 84 of the limiting-recess 83 to thereby check the further turning 15 movement of the said ring 30.

By grasping the finger-piece 82 of the limiting-plunger 78 and drawing outwardly upon the same so as to retire the said plunger out of the limiting-recess 83, the said chaser-operating ring may be turned to a further degree to completely disengage its cam-lugs 29 from the respective notches 28 in the chasers 27, to thus permit the radial removal of the said chasers from the grooves 26 in the chaser-carrying member 25.

The die head structure herein shown is capable of being tripped by two distinct methods, i. e., by the relative forward draft exerted by the work upon the chasers 27, and by the engagement of the head 60 of the tripping-screw 59 with a suitable abutment 35 (Fig. 5), all in a manner as will hereinafter be described.

With the parts positioned as is shown particularly well in Figs. 2 and 4, the die head is ready for a threading operation since the chasers 27 are projected inwardly into their advanced or thread-cutting positions and the latch-pin 53 by its engagement with the latching-abutment 52 of the chaser-operating ring 30 serves to rigidly but releasably hold the said chasers in the position referred to.

With the shank 21 of the mounting-member 20 firmly clamped in the turret of a screw-machine 45 or other suitable holder, let it be assumed that the work to be threaded is rotated with respect to the die head structure which latter is held stationary save for axial movement required to engage its chasers 27 with the work. 50

Let it now be assumed that it is desired to effect a tripping of the die head by means of an abutment such as the abutment 85 shown by broken lines in Fig. 5. Under these conditions, as the die head structure is fed onto the work, the head 55 of the tripping-screw 59 will, after a predetermined axial travel of the die head, engage with the abutment 85 (Fig. 5). When this occurs, the forward travel of the said tripping-screw as well as the latch-member 55, will be halted while the 60 remainder of the die head structure continues to move axially forwardly onto the work. As the die head structure (with the exception of the tripping-screw 59 and the parts connected thereto) continues its forward travel relative to the 65 work, the locking-abutment 52 carried by the chaser-operating ring 30, will move forwardly out of engagement with the latching-pin 53. At the instant the latching-abutment 52 reaches the position with respect to the latching-pin 53 shown 70 in Fig. 5, the said latching-abutment 52 and the entire chaser-operating ring 30 will be freed of restraint and the chaser-retracting spring 46 will act to turn the said chaser-operating ring in a clockwise direction until the limiting-plunger 78 75

engages with the endwall 84 of the limiting-recess 83 (Fig. 6).

By the movement above described, the cam-lugs 29 of the chaser-operating ring 30 will have been moved in a clockwise direction and will, by virtue of their coupling with the said chasers through the intermediary of the notches 28, effect the retraction or retirement of the said chasers into the positions in which they are indicated by broken lines in Fig. 2. The work just threaded and the die head may now be axially separated and the die head reset preparatory to another threading operation.

The die head may be reset for another threading operation by turning the chaser-operating ring 30 in a counter-clockwise direction against the tension of the chaser-retracting spring 46, by means of force applied to a resetting-lug 86 rigid with and radially projecting from the outer surface of the said chaser-operating ring 30.

To effect the tripping of the die head by means of the work itself rather than by means of an extraneous abutment such as the abutment 85, the following procedure may be followed.

After the die head has been threaded onto the work to the desired extent, the axial advance of the mounting-member 20 with respect to the work may be halted. The continued rotary movement of the work represented by broken lines 87 in Fig. 9 will, however, draw forwardly upon the chasers and hence upon the unit which comprises in the main, the chaser-carrying member 25, chaser-operating ring 30 and retaining-plate 31. Meanwhile, however, the tripping-screw 59 and the parts rigid therewith will be held stationary by the engagement of the coupling-nut 66 with the bottom of the recess 65.

Ultimately the latching-abutment 52 carried by the chaser-operating ring 30 will move forwardly clear of the latching-pin 53 which is now held stationary, until the parts reach the positions in which they are indicated in Fig. 9 whereupon the chaser-retracting spring 46 will be free to turn the said ring and effect the retirement of the chasers 27 in the manner before described.

As will be obvious from the foregoing, the tripping-point of the die head may be conveniently adjusted by varying the position of the tripping-screw 59 with respect to the latch-member 55.

Attention may here be called to the fact that regardless of the mode of tripping utilized, the initial engagement between the chasers 27 and the work may be cushioned, so to speak, by permitting free play to the cushioning-plungers 41. If, for any reason, it should be desired to nullify this cushioning action, the stop-screw 43 may be projected into the position in which it is shown in Fig. 1 to normally engage the rear face of the retaining-plate 31 to thereby prevent the unit comprising the said retaining-plate, chaser-carrying member 25 and chaser-operating ring 30, from moving rearwardly further than as is indicated in Fig. 1.

By providing a latch-member 55 or its equivalent and the associated parts, an extremely-rigid and precision-performing structure is provided which eliminates many of the objections to prior types of self-opening die heads.

The invention may be carried out in other specific ways than those herein set forth without departing from the spirit and essential characteristics of the invention, and the present embodiments are, therefore, to be considered in all respects as illustrative and not restrictive, and

all changes coming within the meaning and equivalency range of the appended claims are intended to be embraced therein.

I claim:

1. A self-opening die head including in combination: a chaser-carrying member; chasers movably mounted in the said chaser-carrying member; an oscillating chaser-operating member associated with the said chaser-carrying member and operatively connected to the said chasers for controlling the movement thereof; spring-means urging the said chaser-operating member into position to retire the said chasers; and a releasable L-shaped latch-member bodily movable with respect to the said chaser-operating member and having a portion engageable with a portion of the latter to releasably hold the same in position to maintain the said chasers in their advanced positions, the said L-shaped latch-member having one arm extending substantially radially with respect to the die head structure and another arm extending in substantial parallelism with the axis thereof and over the exterior of the said chaser-operating member.

2. A self-opening die head including in combination: a chaser-carrying member; chasers movably mounted in the said chaser-carrying member; an oscillating chaser-operating member associated with the said chaser-carrying member and operatively connected to the said chasers for controlling the movement thereof; spring-means urging the said chaser-operating member into position to retire the said chasers; a releasable L-shaped latch-member bodily movable with respect to the said chaser-operating member and having a portion engageable with a portion of the latter to releasably hold the same in position to maintain the said chasers in their advanced positions, the said L-shaped latch-member having one arm extending substantially radially with respect to the die head structure and another arm extending in substantial parallelism with the axis thereof and over the exterior of the said chaser-operating member; and a tripping-member carried by the arm of the said L-shaped latch-member which extends over the said chaser-operating member, the said tripping-member being adjustable forwardly and backwardly with respect to the said arm and designed and adapted for engagement with a tripping abutment.

3. A self-opening die head including in combination: a chaser-carrying member; chasers movably mounted in the said chaser-carrying member; an oscillating chaser-operating member associated with the said chaser-carrying member and operatively connected to the said chasers for controlling the movement thereof; spring-means urging the said chaser-operating member into position to retire the said chasers; a releasable L-shaped latch-member bodily movable with respect to the said chaser-operating member and having a portion engageable with a portion of the latter to releasably hold the same in position to maintain the said chasers in their advanced positions, the said L-shaped latch-member having one arm extending substantially radially with respect to the die head structure and another arm extending in substantial parallelism with the axis thereof and over the exterior of the said chaser-operating member; and a tripping-screw extending in substantial parallelism with the axis of the die head and threaded-connected to the arm of the said

L-shaped latch-member which extends over the said chaser-operating member, in position to engage with an external tripping abutment.

4. A self-opening die head including in combination: a chaser-carrying member; chasers movably mounted in the said chaser-carrying member; an oscillating chaser-operating member associated with the said chaser-carrying member and operatively connected to the said chasers for controlling the movement thereof; spring-means urging the said chaser-operating member into position to retire the said chasers; a releasable L-shaped latch-member bodily movable with respect to the said chaser-operating member and having a portion engageable with a portion of the latter to releasably hold the same in position to maintain the said chasers in their advanced positions, the said L-shaped latch-member having one arm extending radially with respect to the die head structure and a tubular arm extending in substantial parallelism with the axis of the said chaser-operating member and over the exterior thereof; and an adjusting-screw threaded into the tubular arm of the said L-shaped latch-member with capacity for adjustment therein and in position to engage with an external abutment.

5. A self-opening die head comprising: a chaser-carrying member; chasers movably mounted in the said chaser-carrying member; a chaser-operating ring mounted with capacity for oscillatory-movement upon the said chaser-carrying member in a plane substantially perpendicular to the axis of the die head structure; spring-means urging the said chaser-operating ring to turn into position to retire the said chasers; a retaining-plate secured to the said chaser-carrying member in position to hold the said chaser-operating ring thereon against axial displacement; and an L-shaped releasable latch-member having a portion extending through the said retaining-plate into position to engage a portion of the said chaser-operating ring to hold the same in position to maintain the said chasers in their advanced positions, the said L-shaped latch-member being also provided with means extending forwardly over the exterior periphery of the said oscillating chaser-operating ring in position to be engaged by an external abutment.

6. A self-opening die head comprising: a chaser-carrying member; chasers movably mounted in the said chaser-carrying member; a chaser-operating ring mounted with capacity for oscillatory-movement upon the said chaser-carrying member in a plane substantially perpendicular to the axis of the die head structure; spring-means urging the said chaser-operating ring to turn into position to retire the said chasers; a retaining-plate secured to the said chaser-carrying member in position to hold the said chaser-operating ring thereon against axial displacement and provided with an eccentric tubular-portion extending over the said chaser-operating ring; and a releasable latch-member having a portion moving in the tubular-portion of the said retaining-plate and also having a portion engageable with a portion of the said chaser-operating ring to releasably hold the same in position to maintain the said chasers in their advanced positions.

7. A self-opening die head comprising: a chaser-carrying member; chasers movably mounted in the said chaser-carrying member; a chaser-operating ring mounted with capacity for oscillatory-movement upon the said chaser-

carrying member in a plane substantially perpendicular to the axis of the die head structure; spring-means urging the said chaser-operating ring to turn into position to retire the said chasers; a retaining-plate secured to the said chaser-carrying member in position to hold the said chaser-operating ring thereon against axial displacement and provided with a tubular-portion extending over the said chaser-operating ring; and a releasable latch-member having a portion moving in the tubular-portion of the said retaining-plate and also having a portion extending through the said retaining-plate into position to engage a portion of the chaser-operating member to hold the same in position to maintain the said chasers in their advanced positions.

8. A self-opening die head comprising: a chaser-carrying member; chasers movably mounted in the said chaser-carrying member; a chaser-operating ring mounted with capacity for oscillatory-movement upon the said chaser-carrying member in a plane substantially perpendicular to the axis of the die head structure; spring-means urging the said chaser-operating ring to turn into position to retire the said chasers; a retaining-plate secured to the said chaser-carrying member at the rear of and in position to hold the said chaser-operating ring thereon against axial displacement and having a tubular-portion extending forwardly over the said chaser-operating ring; and a releasable latch-member having a portion movable in the tubular-portion of the said retaining-plate, the said latch-member also having a portion located inwardly with respect to its said tubular-portion and extending forwardly through the said retaining-plate into position to engage a portion of the said chaser-operating ring to hold the same in position to maintain the said chasers in their advanced positions.

9. A self-opening die head comprising: a chaser-carrying member; chasers movably mounted in the said chaser-carrying member; a chaser-operating ring mounted with capacity for oscillatory-movement upon the said chaser-carrying member in a plane substantially perpendicular to the axis of the die head structure; spring-means urging the said chaser-operating ring to turn into position to retire the said chasers; a retaining-plate secured to the said chaser-carrying member in position to hold the said chaser-operating ring thereon against axial displacement and having a tubular-portion extending forwardly over the said chaser-operating ring; a releasable latch-member having an internally-threaded tubular-portion movable in the tubular-portion of the said retaining-plate, the said latch-member also having a portion engageable with a portion of the said chaser-operating ring to hold the same in position to maintain the said chasers in their advanced positions; and an adjusting-screw threaded into the tubular-portion of the said latch-member with capacity for axial adjustment therein and in position to engage with an external abutment.

10. A self-opening die head comprising: a chaser-carrying member; chasers movably mounted in the said chaser-carrying member; a chaser-operating ring mounted with capacity for oscillatory-movement upon the said chaser-carrying member in a plane substantially perpendicular to the axis of the die head structure; spring-means urging the said chaser-operating ring to turn into position to retire the said chasers.

chasers; a retaining-plate secured to the said chaser-carrying member in position to hold the said chaser-operating ring thereon against axial displacement and having a tubular-portion 5 extending forwardly over the said chaser-operating ring; a releasable latch-member having a tubular-portion movable in the tubular-portion of the said retaining-plate, the said latch-member also having a portion located inwardly with 10 respect to its said tubular-portion and extending forwardly through the said retaining-plate into position to engage a portion of the said chaser-operating ring to hold the same in position to maintain the said chasers in their advanced positions; and an adjusting-screw 15 extending through the tubular-portion of the said latch-member and projecting from both ends thereof with capacity for axial adjustment therein and in position to engage with a tripping- 20 abutment.

11. A self-opening die head comprising: a chaser-carrying member; chasers movably mounted in the said chaser-carrying member; a chaser-operating ring mounted with capacity for 25 oscillatory-movement upon the said chaser-carrying member in a plane substantially perpendicular to the axis of the die head structure; spring-means urging the said chaser-operating ring to turn into position to retire the said 30 chasers; a retaining-plate secured to the said chaser-carrying member in position to hold the said chaser-operating ring thereon against axial displacement and having a tubular-portion 35 extending forwardly over the said chaser-operating ring; a releasable latch-member having a tubular-portion movable in the tubular-portion of the said retaining-plate, the said latch-member also having a portion engageable with a portion 40 of the said chaser-operating ring to hold the same in position to maintain the said chasers in their advanced positions; and a latch-spring located within the tubular-portion of the said retaining-plate and yieldingly urging the said 45 latch-member into position to latch the said chaser-operating ring.

12. A self-opening die head comprising: a chaser-carrying member; chasers movably mounted in the said chaser-carrying member; a chaser-operating ring mounted with capacity for 50 oscillatory-movement upon the said chaser-carrying member in a plane substantially perpendicular to the axis of the die head structure; spring-means urging the said chaser-operating ring to turn into position to retire the said 55 chasers; a retaining-plate secured to the said chaser-carrying member in position to hold the said chaser-operating ring thereon against axial displacement and having a tubular-portion 60 extending forwardly over the said chaser-operating ring; a releasable latch-member having a portion movable in the tubular-portion of the said retaining-plate, the said latch-member also having a portion engageable with a portion of the said chaser-operating ring to hold the same 65 in position to maintain the said chasers in their advanced positions; a tubular spring-plunger movable in the tubular-portion of the said retaining-plate and surrounding the portion of the said latch-member which is movable therein; 70 and a latch-spring housed within the tubular-portion of the said retaining-plate and thrusting against the said tubular spring-plunger to yieldingly urge the said latch-member into position to restrain the said chaser-operating ring.

13. A self-opening die head comprising: a

mounting-member; a chaser-carrying member carried by the said mounting-member with capacity for axial movement with respect thereto; chasers movably mounted in the said chaser-carrying member; an oscillating chaser-operating member carried by the said chaser-carrying member with capacity for oscillatory-movement in a plane substantially perpendicular to the axis of the said chaser-carrying member; spring-means urging the said chaser-operating member 5 into position to retire the said chasers; and an L-shaped releasable latch-member bodily movable with respect to the said chaser-operating member and having a portion engageable with a portion of the latter to releasably hold the same in position to maintain the said chasers in their advanced positions, the said L-shaped latch-member having one arm extending substantially radially with respect to the die head structure and another arm extending in substantial parallelism with the axis thereof and over the exterior of the said chaser-operating member. 15

14. A self-opening die head comprising: a mounting-member; a chaser-carrying member 25 carried by the said mounting-member with capacity for axial movement with respect thereto; chasers movably mounted in the said chaser-carrying member; an oscillating chaser-operating member carried by the said chaser-carrying 30 member with capacity for oscillatory-movement in a plane substantially perpendicular to the axis of the said chaser-carrying member; a retaining-plate secured to the said chaser-carrying member in position to hold the said chaser-operating 35 member thereon; spring-means urging the said chaser-operating member into position to retire the said chasers; an L-shaped releasable latch-member bodily movable with respect to the said chaser-operating member and having a portion 40 engageable with a portion of the latter to releasably hold the same in position to maintain the said chasers in their advanced positions, the said L-shaped latch-member having one arm extending substantially radially with respect to the die 45 head structure and another arm extending in substantial parallelism with the axis thereof and over the exterior of the said chaser-operating member; and a tripping-screw projecting rearwardly from the said L-shaped latch-member 50 into position to be engaged by a portion of the said retaining-plate to halt the relative forward movement of the said latch-member when the said chaser-carrying member is moved forwardly with respect to the said mounting-member by 55 forward draft exerted by the work being threaded, to effect the release of the said chaser-operating member.

15. A self-opening die head comprising: a mounting-member; a chaser-carrying member 60 carried by the said mounting-member with capacity for axial movement with respect thereto; chasers movably mounted in the said chaser-carrying member; an oscillating chaser-operating member carried by the said chaser-carrying 65 member with capacity for oscillatory-movement in a plane substantially perpendicular to the axis of the said chaser-carrying member; spring-means urging the said chaser-operating member into position to retire the said chasers; a latch-member having projecting portions extending in 70 parallel relation from an arm thereof, one of the said projecting portions releasably holding the said chaser-operating member in position to maintain the said chasers in their advanced positions. 75

5 tions; spring-means urging the said chaser-carrying member rearwardly with respect to the said mounting-member; and second spring-means of relatively-limited scope-of-movement and urging the said chaser-carrying member forwardly with respect to the said mounting-member and providing a cushion receiving the initial thrust upon the said chaser-carrying member occurring as a result of the engagement of the 10 said chasers with the work.

15 16. A self-opening die head comprising: a mounting-member; a chaser-carrying member carried by the said mounting-member with capacity for axial movement with respect thereto; chasers movably mounted in the said chaser-carrying member; an oscillating chaser-operating member carried by the said chaser-carrying member with capacity for oscillatory-movement in a plane substantially perpendicular to the axis 20 of the said chaser-carrying member; spring-means urging the said chaser-operating member

5 into position to retire the said chasers; a latch-member having projecting portions extending in parallel relation from an arm thereof, one of the said projecting portions releasably holding the said chaser-operating member in position to maintain the said chasers in their advanced positions; spring-means urging the said chaser-carrying member rearwardly with respect to the said mounting-member; second spring-means of relatively-limited scope-of-movement and urging the 10 said chaser-carrying member forwardly with respect to the said mounting-member and providing a cushion receiving the initial thrust upon the said chaser-carrying member occurring as a result of the engagement of the said chasers with the work; and a limiting-screw extendable between the said chaser-carrying member and the said mounting-member to form a positive stop for the former and to eliminate the action of the 15 said second spring-means.

20 ALBERT F. BREITENSTEIN.
